[57] CLAIM

The ornamental design for a circle cutting jig, as shown and described.

DESCRIPTION

FIG. 1 is an isometric view of the circle cutting jig

constructed according to the present invention with the members thereof assembled in a first configuration; FIG. 2 is a front elevational view of the circle cutting jig illustrated in FIG. 1;

FIG. 3 is a rear elevational view of the circle cutting jig illustrated in FIG. 1;

FIG. 4 is a right side elevational view of the circle cutting jig illustrated in FIG. 1;

FIG. 5 is a left side elevational view of the circle cutting jig illustrated in FIG. 1;

FIG. 6 is a top view of the circle cutting jig illustrated in FIG. 1;

FIG. 7 is a bottom view of the circle cutting jig illustrated in FIG. 1;

FIG. 8 is an isometric view of the circle cutting jig constructed according to the present invention with the members thereof assembled in a second configuration; FIG. 9 is a front elevational view of the circle cutting jig illustrated in FIG. 8;

FIG. 10 is a rear elevational view of the circle cutting jig illustrated in FIG. 8;

FIG. 11 is a right side elevational view of the circle cutting jig illustrated in FIG. 8;

FIG. 12 is a left side elevational view of the circle cutting jig illustrated in FIG. 8;

FIG. 13 is a top view of the circle cutting jig illustrated in FIG. 8; and,

FIG. 14 is a bottom view of the circle cutting jig illustrated in FIG. 8.
